CLAIM

The ornamental design for a pipe and tube cleaning kit, as shown and described.

DESCRIPTION

FIG. 1 is a front elevational view of a pipe and tube cleaning kit showing my new design;

FIG. 2 is a rear elevational view thereof;

FIG. 3 is a top plan view thereof;

FIG. 4 is a bottom plan view thereof; and,

FIG. 5 is a perspective view of my kit.

The dotted lines showing a drill in FIG. 5 are for illustrative purposes only and form no part of my claimed design.
